CLAIM

The ornamental design for a solid state surge protector module for telephone communication lines, as shown and described.

DESCRIPTION

FIG. 1 is an isometric view of a solid state surge protector module for telephone communication lines showing my new design;

FIG. 2 is a side elevational view thereof, the opposite side elevational view being a mirror image;

FIG. 3 is a front elevational view thereof;

FIG. 4 is an isometric view of a solid state surge protector module for telephone communication lines, viewed from the rear;

FIG. 5 is a top view of the device shown in FIGS. 1 and 4; and,

FIG. 6 is a bottom view of the device shown in FIGS. 1 and 4.
